Homan & Homan

Patented Mar. 23, 1926.

1,578,114

UNITED STATES PATENT OFFICE.

THOMAS J. FEGLY, OF PHILADELPHIA, PENNSYLVANIA, ASSIGNOR TO NORTH BRO'S M'F'G CO., OF PHILADELPHIA, PENNSYLVANIA, A CORPORATION OF PENNSYLVANIA.

AUXILIARY HANDLE FOR WRENCHES.

Application filed March 25, 1922. Serial No. 546,732.

To all whom it may concern:

Be it known that I, THOMAS J. FEGLY, a citizen of the United States, residing in Philadelphia, Pennsylvania, have invented 5 certain improvements in Auxiliary Handles for Wrenches, of which the following is a specification.

The object of my invention is to provide an auxiliary handle, which can be attached 10 to the handle of a wrench when said handle is used as an extension member of a socket wrench. The handle illustrated in the drawings is fully described and claimed in an application for patent for a socket wrench 15 filled by George O. Leopold on the tenth day of March, 1922, under Serial No. 542, 661.

In the accompanying drawings:

Fig. 1 is a perspective view showing my 20 improved auxiliary handle applied to the handle of a socket wrench;

Fig. 2 is a view showing the handle attached to a socket member of a wrench;

Fig. 3 is a sectional view of the auxiliary 25 handle, the section being on the line 3—3, Fig. 4, with the handle in elevation;

Fig. 4 is a sectional view on the line 4—4, Fig. 3;

Fig. 5 is a sectional view on the line 5—5, 30 Fig. 3; and

Fig. 6 is a detached view, in elevation, of the hub of the auxiliary handle.

Referring to the drawings, 1 is the handle 35 of a socket wrench, such as set forth in the above mentioned application for patent. This handle is rectangular in cross section and has a reduced end 2 with spring-pressed balls 3 therein, which are arranged to enter a recess in the walls of an opening in the 40 socket member. The other end of the handle has an angular extension 2^a, shaped as shown in Fig. 2, so that it will enter a recess 4 in a socket member 5. In the extension 2^a are spring-pressed balls 6, shown clearly 45 in Fig. 4, which enter recesses 7 in the socket member. These balls act as pivots for the handle so that the handle can be moved to a limited extent in the recess. This construction is fully described in the application 50 for patent hereinbefore referred to.

In some instances, it is desirable to use the wrench handle 1 as an extension member of a socket wrench. In this case, the end 2 is placed in a recess in a socket and

in order to turn the handle with force, the 55 auxiliary handle, forming the subject of this invention, is applied to the end of the handle having the angular extension, as shown in Fig. 1.

8 is a hub forming part of the auxiliary 60 handle. This hub has a rectangular socket 9, open at one side, as at 10. The angular end of the handle is passed into the socket and turned so that the extension 2^a will project through the side opening 10, as clearly 65 shown in Fig. 3, the parts being so proportioned that the surface 11 of the extension 2^a will bear against the surface 12 of the hub member 8.

13 are balls located in an opening in the 70 end of the handle 1. Back of these balls is a spring 14, which tends to force the balls out into grooves 15 in the walls of the socket 9 of the hub so as to retain the handle firmly in the socket. As the balls are yieldingly mounted in the socket, the handle can 75 be withdrawn by force.

In the upper portion of the hub 8 is a transverse opening 16 through which extends a cross bar 17. This bar has a groove 80 18 at the center and grooves 19 near each end. At the grooves are depressions 20 to receive a ball 21, which is located in a socket 22 in the hub 8. Back of the ball 21 is a spring 23, which tends to force the ball 85 against the cross bar 17. When the ball is in one of the recesses of the cross bar, the bar is yieldingly held in position.

It will be seen by the above construction 90 that, when it is desired to use the handle as a straight extension for a socket, the hub of the auxiliary handle can be attached to the angular end of the handle 1 and the socket member can be turned by the cross bar of the hub, the balls yieldingly holding 95 the handle in the hub and the balls 3 yieldingly holding the socket to the end of the handle.

When it is desired to use the handle independently of the auxiliary handle, then the 100 hub is detached from the main handle and the angular end is inserted in the recess in the socket member, as illustrated in Fig. 2.

I claim:

1. The combination with a handle having 105 an angularly disposed extremity provided with an inclined face, of an auxiliary handle comprising a hub provided with a socket

for mounting on said handle, the wall of said socket having a side opening to accommodate the angularly disposed extremity of the handle, there being an inclined bearing carried by the auxiliary handle and cooperating with the inclined face of the extremity of the handle whereby to maintain the parts in alignment.

2. The combination with a handle having an angularly disposed extremity provided with an inclined face, of an auxiliary handle comprising a hub provided with a socket for mounting on said handle, the wall of said socket having a side opening to accommodate the angularly disposed extremity of the handle, the wall of said side opening being inclined to provide a bearing to cooperate with the inclined face of the extremity of

the handle whereby to maintain the parts in alignment.

3. The combination of a handle having an angularly disposed end, the end having an inclined surface; an auxiliary handle having a hub and a cross bar, the hub having a rectangular socket to receive the handle, the wall of the socket having an opening at one side to receive the angularly disposed end of the handle, the upper wall of the side opening forming a bearing surface for the inclined surface of the handle, said handle having a transverse opening; balls located in the opening; and a spring between the balls, the walls of the socket in the hub of the auxiliary handle having grooves to receive the balls.

THOMAS J. FEGLEY.
